The ornamental design for a jacket, as shown and described.

DESCRIPTION

FIG. 1 is a front view of a jacket showing our new design; FIG. 2 is a perspective view thereof;

FIG. 3 is a front view thereof showing the state where the zipper is partly closed;

FIG. 4 is an enlarged fragmentary view of FIG. 1;

FIG. 5 is an enlarged fragmentary view of FIG. 2; and, FIG. 6 is an enlarged fragmentary view of FIG. 3.

The dashed broken lines in the drawings are for the purpose of illustrating unclaimed portions of the jacket and form no part of the claimed design, and the dash-dot-dash broken lines in the drawings illustrate the boundary of the claimed design. The fine pitch dotted line in the claimed portion shows stitching.
